UNITED STATES PATENT OFFICE

DAVID E. LEASURE, OF LOS ANGELES, CALIFORNIA, ASSIGNOR OF ONE-HALF TO ROY E. LEASURE, OF VENTURA, CALIFORNIA

BATTERY TONGS

Application filed July 13, 1928. Serial No. 292,445.

My invention relates to tools, and more particularly to such tools as function as battery tongs whereby the terminals of a battery may be quickly and expeditiously removed.

It accordingly is an object of my invention to provide a novel form of battery tongs having a stationary jaw adapted to engage the side of a battery terminal, and a reciprocating member adapted to engage the top of said terminal, means being also provided in the shape of a handle, said handle having means, such as gear teeth to engage a rack on said member so that by manipulating 10 said handle said member and said jaw will coact to expeditiously and quickly remove said terminal.

It is also an object of my invention to provide a movable jaw to operate in conjunction 20 with the stationary jaw and the reciprocating member, either one or two handles, as desired, being provided to operate said reciprocating member and said movable jaw either simultaneously or individually.

Further objects and advantages of my invention, as will hereinafter more fully appear, I attain by the device described in the specification and illustrated on the drawings, forming a part of my application.

Reference is had to the accompanying drawings, in which similar reference characters denote similar parts. In the drawings,

Fig. 1 is a side elevational view of one form of my invention having a movable jaw, with closure of the housing broken away to disclose the internal construction,

Fig. 2 is a top plan view of Fig. 1,

Fig. 3 is a fragmentary view, similar to Fig. 1, but showing another form of my invention in which two operating handles are provided.

Fig. 4 is a fragmentary view of Fig. 1, but showing the position of the parts when the battery terminal is removed,

Fig. 5 is a fragmentary view, similar to Fig. 4, but showing another form of my invention in which there is no movable jaw, and

Fig. 6 is an elevational view showing the

practical application of the tongs depicted in Fig. 3 applied to a battery terminal.

Describing my invention more in detail, I provide a housing 2 (Figs. 1 and 2) having associated therewith in any suitable way, as by rivets 4 or otherwise, a stationary jaw 6, provided with a terminal engaging portion or projection 8, cut away as at 10 (Fig. 2), whereby the side of the terminal 12 of the battery 14 (Fig. 6) may be engaged.

Associated with the casing 2 in any preferred way, as by the pivot 18, is a movable jaw 20, provided with a projection 22, having a cut-away or bifurcated battery terminal engaging part 24 (Fig. 2), said jaw having a curved portion or cam 26 on its lower end for a purpose presently to be described.

Positioned within the housing 2 is a reciprocating member 28, the top part 30 of which is adapted to engage the top of the 70 battery terminal 12', said member having an extension 32 provided with a rack 34 whereby said member may be reciprocated, said member also having a curved portion or cam means 36 adapted to engage the complementary cam means 26 on the movable jaw 20.

To operate the rack 34, an operating handle or member 38, provided with a suitable gear 40, the teeth of which are in engagement with the rack 34, and for the sake of 80 repair or cleaning the housing 2 may be provided with a closure 42, which may be removable by any suitable means as the removable bolts 44, said tongs having also a manipulating handle 46, which handle, if desired, may be integral with the closure 42, or otherwise.

To remove the battery terminal 12, the jaws 6 and 20 are placed over said terminal, the bifurcated portions 10 and 24 engaging 90 the side portions of said terminal (Fig. 6), after which the handle 38, through the gear 40 and rack 34, causes the member 28 to be moved so that its top portion 30 engages the top of said terminal, after which the 95 simultaneous manipulation of the handles 38 and 46 will instantly remove said terminal. Fig. 4 shows the parts in position as the terminal is removed.

In Fig. 3 I have shown a modification in 100

which two operating handles 38' are used to actuate the reciprocating member 28' and movable jaw 20', either individually or simultaneously, so that the movable jaw 20' may coact with the stationary jaw 6', engaging the sides of the battery terminal 12, to remove said terminal, the operation being precisely the same as that of the other form of my invention.

10 The left handle 38' is provided with a gear 40' to engage the rack 34' of the member 28', and the right handle 38' is provided with the engaging means 36', which may be in the form of teeth, to engage the complementary means 26' on the movable jaw 20', said handle being pivoted to the housing 2', as indicated at 48'.

20 Fig. 5 shows another form of my invention in which there is no movable jaw, the housing 2'' having associated therewith in any preferred manner the stationary jaw 6'', the projection 8'' functioning to engage one side of the battery terminal.

25 The casing 2'' is also provided with the reciprocating member 28'' having its upper part 30'' adapted to engage the top of the battery terminal, said member having on the lower portion 32'' thereof the rack 34'' to be engaged by the teeth of the gear 40'' associated with the operating handle 38''. Since the operation of this form of my invention is identical with the others, the description thereof need not be repeated.

30 While I have thus described my invention with great particularity, it will be clear that it may be modified throughout a wide range. I accordingly do not propose to be limited to the exact details of construction shown and described but reserve the right 40 in practice to make any and all modifications thereof that fall within the scope of the appended claims.

I claim as my invention:

1. In a device of the character described, 45 a housing, a stationary jaw on said housing, a movable jaw on said housing, a reciprocating member in said housing, means on said member and on said movable jaw adapted to coact so that said member will 50 actuate said movable jaw, and means associated with said casing for operating said reciprocating member.

2. In a device of the character described, 55 a housing, a stationary jaw on said housing, a movable jaw on said housing, a reciprocating member in said housing, means associated with said member and said movable jaw whereby said member will move said movable jaw, a rack on said member, and a 60 toothed operating member pivoted to said housing for operating said rack to reciprocate said member.

3. A battery tongs comprising a stationary and a movable jaw adapted to engage 65 the sides of a battery terminal, a recipro-

cating member positioned between said jaws and adapted to engage the top of said terminal, a rack on said member, an operating handle for operating said member, a set of gear teeth on said handle for engaging said rack, and a second handle for operating said movable jaw.

4. A battery tongs comprising a stationary and a movable jaw adapted to engage the sides of a battery terminal, a reciprocating member adapted to engage the top of said terminal, a rack on said reciprocating member, an operating handle for operating said rack, gear teeth on said handle for engaging said rack, a second handle for operating said movable jaw, and means on said second handle for operating said movable jaw.

5. In a battery tongs, an elongated handle member having a widened portion forming a casing, and stationary jaw at one end thereof, said jaw being adapted to engage the side of a battery terminal, and below the top thereof, a cover for said casing, a reciprocating member in said casing, said member having a portion adapted to engage the top of said terminal, and elongated means for operating said member, said means being positioned on the stationary jaw side of said casing.

In testimony whereof I have signed my name to this specification.

DAVID E. LEASURE.
